UNITED STATES PATENT OFFICE.

FRANK T. NEWITT, OF PLATTEVILLE, AND SIMEON H. LA PLANT AND LEWIS L. TURNER, OF SALIDA, COLORADO, ASSIGNEES TO THE L. T. N. MANUFACTURING & DEVELOPMENT SYSTEM, OF PLATTEVILLE, COLORADO, A COMMON-LAW TRUST AGREEMENT ORGANIZED UNDER THE LAWS OF COLORADO.

SYSTEM FOR THE PRODUCTION OF OIL GAS.

Application filed March 11, 1924. Serial No. 698,419.

This invention relates to a system for the production of gaseous fuel and its primary object is to provide a practical and economical method of utilizing a volatile liquid hydrocarbon in generating a gaseous mixture adapted for use as a fuel or an illuminant.

A further object of the invention is to produce a fuel of the above stated nature of which aqueous vapor, preferably in the form of steam, is an element and still another object is to provide a system of co-operative devices for the production of a fuel gas by a novel method of diffusing its components.

The method consists briefly in causing the forcible contact of an atomized volatile liquid hydrocarbon and a vapor under pressure in an enclosed space, whereby to effect a rapid and complete volatilization of the liquid while it is being diffused throughout the vapor.

The generated hydrocarbon gas is conducted from the mixing space to the burners of a stove or other heating appliance either directly or by means of a storage reservoir or it may if so desired be utilized as an illuminant by passing it to the burner of a lamp.

An embodiment of a system suitable for use in the performance of the process has been illustrated in the accompanying drawings in which like characters of reference designate corresponding parts throughout the several views and in which.

Figure 1 represents in sectional elevation the system in its preferred form for the utilization of steam and gasoline or other liquid hydrocarbon;

Figure 2, an enlarged sectional elevation of the mixing chamber of the system;

Figure 3, an enlarged vertical sectional view of a check valve adapted for use in preventing the return flow of fluids passing through the system; and

Figure 4, a view similar to Fig. 3 of a pressure regulating valve suitable for use in the system.

Referring to the drawings, the numeral 5 designates a steam boiler heated by a gas burner 6 of conventional construction and provided with a steam outlet which through the medium of a pipe 7 is connected with the gas generating chamber 8. In the form of the invention illustrated in Fig. 1 of the drawing all of the steam from the boiler 5 is

used in the production of the gaseous fuel.

The end of the pipe extends into the chamber in direct opposition to a valve-controlled nozzle 9 at the extremity of a pipe 10 which connects with a source of volatile liquid hydrocarbon such as gasoline, represented by the tank 12.

The gas generating chamber has an oil and gas outlet 13^a which by means of a pipe 13 is connected with a storage reservoir 14 from where the gaseous fuel is connected to the burners of a stove or other heating appliance by means of a pipe 15.

In the construction shown in the drawing a pipe 16 connected with a second outlet of the reservoir 14 conducts a part of the gaseous fuel generated in the operation of the system to the burners of the boiler, pressure regulating valves 17 and 18 of the type illustrated in Figure 4, are connected in the pipes 7 and 10 leading from the boiler and the gasoline tank to the mixing chamber, check valves 19 and 20 such as that shown in Figure 3, prevent the return flow of fluid through the pipes 13 and 10 and hand-valves 21 and 22 control the supply of fuel to the burners through the pipes 15 and 16.

It is advantageous that the hydrocarbon liquid enter the mixing chamber under pressure and the means for creating this pressure have been indicated in the drawing by a simple pump 23 connected with the upper portion of the tank 12 through the medium of a pipe 24. We desire it understood, however, that any other means to forcibly introduce the volatile liquid into the mixing chamber may be employed within the spirit of our invention.

A preferred arrangement of the pipes in the mixing chamber has been illustrated in Figure 2 in which the nozzle 9 at the end of the pipe leading from the gasoline tank, is extended into the pipe through which the steam is supplied from the boiler.

A tapering valve 25 controlling the supply of liquid hydrocarbon has a stem 26 which is slidably supported in a bearing 27 and which extends through a stuffing box 28 on an elbow of the conduit 7 for the adjustment of the valve, it being evident that the valve thus mounted performs the same function as the nozzle-valve shown at 29 in Figure 1. The discharge end of the steam pipe forms a

tubular steam inlet 7^a for the gas generating chamber, and the steam inlet extends through one of the walls of the gas generating chamber past the oil gas outlet 13^a and terminates 5 short of the opposite wall through which extends the nozzle 9 which constitutes the oil inlet and which is of less diameter than the steam inlet pipe 7^a. The nozzle 9 projects into the open end of the steam inlet pipe 7^a and a baffle disk or member 30, which is carried by the stem 26 of the valve 25, is arranged in the path of the discharge of the nozzle 9, and it is of less diameter than the steam inlet pipe and partially constricts the same and 10 forms an annular space for the passage of the steam which flows through the steam inlet pipe 7^a past the baffle disk 30 in the form of an annular stream. The heat of the steam vaporizes the fine oil spray discharged from 15 the nozzle 9 against the baffle disk 30, which diffuses the spray or vapor and causes the same to commingle with the steam, so that the liquid hydrocarbon issues with the steam from the steam inlet pipe 7^a and enters the 20 gas generating chamber in the form of a gas. The generated oil gas passes out through the outlet 13^a. The baffle disk 30 is imperforate except where it is pierced by the stem 26 of the 25 valve 25.

30 In the operation of the system, the violent contact of the two fluids entering the mixing chamber under pressure, causes their intimate diffusion and intermixture in gaseous form it being evident that the heat of the steam is instrumental in causing the rapid and complete vaporization of the liquid which is injected into the chamber through the nozzle in an atomized state.

35 The proportions of the gasoline and steam are easily regulated by means of the valve controlling the issue of gasoline through the nozzle of the pipe 10, and the check-valves and pressure regulating valves hereinbefore referred to, further aid in generating a gaseous fuel the components of which are in the proper ratio for substantially perfect combustion when the gaseous fuel is burned.

40 Having thus described our invention, what we claim and desire to secure by Letters Patent is:

1. A system for the production of oil gas, including in combination, an oil gas generator comprising a gas generating chamber having an oil gas outlet, a steam inlet pipe extending into said chamber through one of the walls thereof past the oil gas outlet and terminating short of the opposite wall and having an open end, an oil inlet extending through the said opposite wall of the gas generating chamber and having a nozzle of a diameter less than the steam inlet pipe and discharging into the same at the open end

thereof, an oil reservoir connected with the oil inlet pipe, and a steam boiler connected with the steam inlet pipe.

2. A system for the production of oil gas, including, in combination, an oil gas generator comprising a gas generating chamber having an oil gas outlet, a steam inlet pipe extending into said chamber through one of the walls thereof past the oil gas outlet and terminating short of the opposite wall and having an open end, an oil inlet pipe extending through the said opposite wall of the gas generating chamber projecting into the open end of the steam inlet pipe and being of a diameter less than the latter, a valve for controlling the discharge nozzle provided with a baffle member arranged in the path of the discharge of said nozzle for diffusing the same, said baffle member being of a diameter less than the steam inlet pipe and forming an intervening space between its periphery and the said outlet pipe for causing the steam to flow past the baffle member in the form of a hollow stream with which the oil commingles in the form of a fine spray, a liquid hydrocarbon reservoir connected with the oil inlet pipe, and a steam boiler connected with the steam inlet pipe.

3. A system for the production of oil gas including, in combination, an oil gas generator comprising a gas generating chamber having an oil gas outlet, a steam inlet pipe extending into said chamber through one of the walls thereof past the oil gas outlet and terminating short of the opposite wall and having an open end, an oil inlet extending through the said opposite wall of the gas generating chamber and having a nozzle projecting into the open end of the steam inlet pipe and being of a diameter less than the latter, a valve for controlling the discharge from the nozzle provided with a stem extending through the steam inlet pipe, guiding means carried by the steam inlet pipe for the steam, a baffle member mounted on the valve stem and arranged in the path of the discharge of the said nozzle for diffusing the oil, said baffle member being of a diameter less than the steam inlet pipe and forming an intervening space between its periphery and the said pipe for causing the steam to flow past the baffle member in the form of a hollow stream with which the oil commingles in the form of a fine spray or vapor, a source of liquid hydrocarbon connected with the oil inlet, and means for supplying the steam inlet pipe with steam.

In testimony whereof we have affixed our signatures.
